Patented May 24, 1921.

UNITED STATES PATENT OFFICE.

JOHN GOOD, OF BROOKLYN, NEW YORK, ASSIGNOR TO GOOD INVENTIONS CO., OF BROOKLYN, NEW YORK, A CORPORATION OF NEW YORK.

INCLOSED COMBUSTION APPARATUS AND METHOD OF IGNITION.

1,379,178.

Specification of Letters Patent.

Patented May 24, 1921.

Application filed August 18, 1917. Serial No. 186,882.

To all whom it may concern:

Be it known that I, JOHN GOOD, United States citizen, residing in Brooklyn, New York, have invented the following-described Improvements in Inclosed Combustion Apparatus and Methods of Ignition.

The invention is an improvement in the structure and method of operating inclosed forced combustion heaters burning liquid fuel and adapted to ignite and burn non-explosively in a space or flame tube of small compass and to be set in operation by the mere pressing of a button or by an equivalent simple operation, whereby the apparatus is adapted for use for preheating the combustion charge mixtures of automobile and boat engines as well as for other uses. The object of the invention is to adapt such apparatus for operation at lower air pressure differences generally, and particularly with a lower pressure difference of the atomizing air used for supplying the fuel to the burner head, and also to simplify the construction and improve the reliability of ignition especially when using heavy fuel liquids or in very cold weather. The several features promoting these and other objects are illustrated in the accompanying drawings, wherein—

30 Figure 1 is a general elevation of an inclosed heater apparatus with parts broken away and shown in section, and including a controlling switch for said apparatus;

Fig. 2 a top plan of the fan blower;

35 Fig. 3 an enlarged detail of the fuel nozzle; and

Fig. 4 a modification.

The electric motor 1 drives a fan blower 2 which is the means for establishing the 40 operating pressure difference in the present case and for this purpose delivers air to the pipe 3 under a pressure therein of say four to seven inches of water. The pipe 3 leads the air to the air admission chamber 4 of the burner head whence it passes through the perforations in the shell 5 into the flame passage, being thereby distributed uniformly around about the flame, as presently explained. A portion of the air from the 50 blower in pipe 3 is caught and deflected by the collector cowl 6 into the air tube 7 and is led thereby to an atomizing nozzle 8 axially disposed in the end of the burner head in atomizing relation to a fuel nozzle

9. The air jet thus produced is of sufficient velocity to aspirate the liquid fuel through the tube of the nozzle 9 from the supply or float chamber 10, which is secured to the lower part of the burner head or disposed below it on some other support. 55 Atomized mixture thus established passes through the distributing shell 5 and into the flame pipe 11, the outer end of which is understood to be freely open to atmosphere at some distance beyond the region 60 of combustion so as not to produce an appreciable back pressure to the flow of spray and air. The burner head and flame pipe 11 will be understood to be entirely closed except for the admission entrances 65 for air and fuel and of course the exhaust outlet, and the fan blower will be understood to be a means for creating and maintaining the flow into and through the burner head and flame pipe, being adapted in 70 the present case to supply the chamber 4 and the tube 7 with air at the same pressure, except as modified by throttle 13, as presently explained. It should be explained that the atomized spray is ignited by a 75 spark at the electrode terminals 12 which directly intercept it and that by reason of the fact that at this place the spray has not yet been thoroughly mixed with the combustion supporting air from the distributor shell 5, such ignition takes place 80 non-explosively and results in a steady flame flowing through the flame pipe 11 with high velocity. The air delivery through the distributor shell 5 is at such 85 rate as to form proportions of fuel and air suited to give complete combustion in the flame passage, that is to say, to give explosive proportions, but without explosion because of the manner of introduction. This 90 adjustment may be attained by manipulation of the valve 13 in the pipe 3 or by a special selection of the size and number of the distributor holes, and is preferably done by the latter method according to the principle explained in another application 95 pending herewith Serial No. 195,506 October 9, 1917, it being understood in either event that a high velocity of the atomizing air jet is desirable not only to lift the fuel 100 liquid from the float chamber, but also to give fine atomization. It is possible to arrange the air and fuel nozzles and the lo- 105

cation of the spark igniter so that the liquid spray will be immediately ignited by the spark even though in an initially cold condition and as in the patent just referred to, but to avoid the necessity for such careful adjustment and for other reasons, reliable ignition is assured in the present case by heating or pre-heating the air or fuel nozzle, or both. In Fig. 1, the fuel nozzle 9, just below its discharge orifice, is surrounded or in contact with an electric heating coil 14, arranged to be put in circuit with the same current source that operates the motor and energizes the spark coil 15 of the igniter, and the circuit of this heating coil is preferably so arranged as to become energized slightly in advance of the motor and spark coil, so that the end of the nozzle will first become hot and will 20 heat the initial discharge of liquid therefrom and render it more readily ignitable, either by reducing its viscosity or partially vaporizing it, or both. A suitable period of advance heating may be determined automatically by the use of a dash-pot-retarded switch such as illustrated in Fig. 1. When the button 15 of this switch is depressed against its spring it first closes the battery circuit through the heating coil 14, and at 30 a later time as determined by the retarding action of the dash-pot 16, closes the circuit through the spark coil and motor. The length of the dash pot barrel and the size of its ports will be understood to be proportioned to produce the effect stated and give an interval of several seconds according to the size of the element and the value of the current available for operating it. The full battery current initially traversing the heating coil 14 raises it and the nozzle quickly to the desired temperature, so that when the motor and ignition circuit is closed by continued pressure on the button 15, the liquid fuel encountering the 40 heated part of the fuel passage will be vaporized thereby and the resulting vapor on issuing into the mixing space within the burner head will become mixed with enough air to render it ignitable and will readily ignite from the spark. Immediately following such ignition the production of vapor is stopped as by discontinuing the current through the element or otherwise, and thereafter the combustion proceeds without vaporization of the liquid prior to its mixture with combustion-supporting air. The heating coil may however remain in circuit during the entire burning period, if desired, this being a matter determined largely by 50 the design of the switch mechanism and if left in the circuit will tend to facilitate combustion by warming the fuel though preferably not to the point of complete vaporization within the fuel nozzle. The preliminary heating of the fuel nozzle and the

conversion of the initial fuel discharge into vaporous form so improves the ignitability of the fuel as to render unnecessary the use of atomizing air jets of higher pressure than can be conveniently obtained from a 70 rotary fan as the air source and is therefore a means for eliminating the need for extremely fine spray orifices for the fuel jet.

The fuel shattering effect produced by the air jet and the mixture of the fuel with air are further enhanced, according to the present invention, by admitting a small quantity of air into the tube of the fuel nozzle 9 above the liquid level in the float bowl. Such air is admitted through the nick 17 (Fig. 3) filed in the tube of the fuel nozzle, and mixes with the column of liquid fuel in the tube, and by reducing the weight of the column makes it more easily liftable by the aspirating action of the air jet, and at the same time improves the atomization. Conversely, the reduction of weight accomplished in the manner stated may be useful to enable a given air jet velocity to lift the liquid to a greater height. 90

Both the preheating of the nozzle and the mixing of air with the liquid column are, individually, means for improving the atomization and the automatic ignition in the closed burner head, and they are used cumulatively for this purpose in the case illustrated, because the vaporization by heating is more effective when the fuel is broken up by bubbles, and for this reason it is intended that this patent shall cover the said features 100 independently and jointly.

Fig. 4 illustrates the further application of the principle of the invention to the pre-heating of the atomizing air itself as by means of a coil 18 applied to the air tube 105 leading to the air jet nozzle 8. A sufficient amount of heat imparted to the air alone will suffice to give reliable spark ignition of a spray otherwise ignitable only as the result of very careful adjustment or of a very powerful (and expensive) spark, and such air heating may be used cumulatively with the fuel nozzle heating as also indicated in the same figure.

While in both the forms above described the preliminary heating of the fuel supply means is desirable for reasons having to do with cleanliness of operation and of apparatus, it should be explained that ignition will also obtain even though the heating does not commence until the fuel supply. The slight accumulation of liquid in the burner head while the latter is warming up, will be subsequently consumed. 115

In certain respects the apparatus shown herein and above described is similar to that shown in my co-pending application Serial No. 186,881, filed August 18th, 1917. 125

Claims.

1. The method of igniting burners of the 130

- kind having fuel and air entrances adapted for mixing and burning fuel liquid with combustion-supporting air without vaporization of the fuel previous to such mixture, 5 which consists in applying heat to vaporize the fuel liquid, mixing the resulting vapor with air, igniting the mixture and thereafter continuing the supply of fuel in liquid form.
- 10 2. The method of igniting burners of the kind having a fuel passage arranged for mixing fuel in liquid form with the combustion-supporting air, which consists in heating the fuel passage to vaporize the fuel liquid flowing therein, mixing the vapor with air, igniting such mixture and thereafter passing fuel in liquid form through said passage.
- 15 3. The method of igniting and operating liquid fuel burners having a mixing space and fuel and air entrances and adapted for mixing and burning liquid fuel without vaporization of the fuel previous to such mixture, which consists in commingling a 20 small amount of air with the fuel liquid, flowing to said space, applying heat to the commingled fuel and air to vaporize the fuel therein igniting the vapor on arrival in said mixing space and thereafter passing un- 25 vaporized fuel liquid into said space.
4. The method of starting the operation of liquid fuel burners of the type in which fuel liquid is atomized into the ignition and combustion space, which consists in initially 30 heating a part of the burner mechanism to vaporize some of the fuel liquid, mixing such vapor with enough air in the burner to render it ignitable, igniting said vaporous mixture and causing the combustion so 35 started to inflame the atomized unvaporized fuel liquid.
5. Liquid fuel combustion apparatus comprising an ignition and mixing space, a fuel passage adapted to discharge liquid fuel 40 spray into said space, means for causing air flow into said space in mixing relation to the liquid spray therein, an igniter in said space and means independent of the combustion in said space for heating said passage and causing temporary discharge of fuel vapor therefrom to facilitate ignition.
6. Liquid fuel combustion apparatus comprising an ignition and mixing space, means for causing air flow into said space, 45 a fuel passage adapted to deliver liquid fuel into said space in substantially constant proportion to the air flow and control means for said apparatus adapted for temporarily heating said passage to cause delivery of hot fuel vapor instead of liquid spray.
7. Inclosed combustion apparatus comprising means for mixing and burning liquid fuel and air without vaporization of the fuel prior to such mixture, in combination with means for igniting said mixture 50
- comprising an igniter element in said space and a heating element adapted to vaporize the fuel liquid and produce fuel vapor in said space.
8. Inclosed combustion apparatus having 70 means for creating air flow thereinto and means controlled by said flow for proportionately delivering fuel liquid thereinto, in combination with an electric heating element for the fuel delivery means and an 75 electric igniter located to ignite the fuel vapor produced by said element.
9. Inclosed combustion apparatus having means for creating air flow thereinto and means controlled by such flow for proportionately delivering fuel liquid thereinto, 80 in combination with an electric heating element for vaporizing the fuel liquid, an igniter for the fuel vapor and automatic means for energizing said element in ad- 85 vance of fuel delivery.
10. Combustion apparatus comprising a burner head, an air jet nozzle therein, a fuel passage and nozzle leading to said air jet, an air-distributing means surrounding 90 the axis of the air jet, an electric heating element applied to one of said nozzles and an electric igniter within the head.
11. Combustion apparatus comprising a burner head having a means for producing 95 a liquid spray, means for mixing combustion supporting air with the spray, an electric igniter, an electric heater element adapted to vaporize the fuel liquid, and a single means for conjointly energizing said ele- 100 ment and igniter.
12. In inclosed liquid fuel combustion apparatus, the combination with an inclosed flame passage having an electric motor-driven fan for creating flow of fuel and air 105 therethrough and containing an electric igniter for the fuel, of an electric heating coil applied to the fuel supplying means and adapted for initially heating the fuel to render the same ignitable by sparks, and 110 switch mechanism adapted for closing the circuit to the heating coil before closing the circuit to the fan and igniter.
13. In inclosed liquid fuel combustion apparatus, the combination with an inclosed 115 flame passage having an electrically driven means for creating flow of fuel and air thereto and therethrough and containing an electric igniter for the fuel, of electric means for initially heating said fuel to render it readily ignitable, and a single switch mechanism controlling said electric means and comprising a delayed action operating member adapted to close the circuit to the heating means before closing it to the other 120 125 of said means.
14. In inclosed liquid fuel combustion apparatus, the combination with a closed burner head having entrances for atomizing and combustion-supporting air and for 130

liquid fuel and containing an electric spark igniter, of means for assisting the ignition of the fuel in said closed head comprising an electric heating coil applied to the fuel entrance and means for admixing air with the fuel flowing toward said heating coil.

15. In inclosed liquid fuel combustion apparatus, the combination with a closed burner head having entrances for atomizing 10 and combustion-supporting air and for liquid fuel, the fuel entrance being in atomizing relation to the atomizing air entrance, said head containing an electric igniter intercepting the atomized spray, of means for 15 promoting the vaporization and atomization of the liquid fuel consisting of means for admitting air to the liquid fuel flowing to said fuel entrance.

16. In inclosed liquid fuel combustion 20 apparatus, a closed burner head containing the orifices of atomizing air and liquid fuel nozzles, an electric igniter and an entrance for combustion supporting air, and a single blower apparatus for directly establishing 25 flow through said nozzles and entrance in combination with electric means for heating and vaporizing the liquid fuel to facilitate the ignition thereof within the said head.

17. Liquid fuel combustion apparatus having a mixing space provided with means 30 for admitting fuel and air thereto and containing an igniter, in combination with a heating element for vaporizing the fuel and means for automatically causing said heating element to function slightly in advance 35 of the admission of fuel to said space.

18. In liquid fuel combustion apparatus, the combination with a burner head containing means for making an ignitable mixture of 40 liquid fuel and air and containing electric means for igniting such mixture, of a passage for supplying the fuel liquid to said head and means for commingling air with the liquid flowing in said passage.

45 19. In liquid fuel combustion apparatus, the combination with an ignition and mixing space provided with means for admitting combustion-supporting and fuel-atomizing air and with an electric igniter, of a passage for conducting fuel liquid into atomizing relation to said air and means for commingling air with the liquid in said passage.

20. Liquid fuel combustion apparatus comprising an air jet, a liquid fuel passage 55 through which liquid fuel is drawn by the action of said jet and an opening in said passage through which air is drawn and commingled with the liquid in said passage.

60 21. In liquid fuel combustion apparatus, an igniter and mixing space, means for admitting combustion, supporting air thereto, and means for supplying liquid fuel thereto comprising a liquid fuel chamber at a 65 lower level, a passage to lead fuel therefrom

to said space, and means for admitting a gaseous medium to said passage for admixture with the liquid flowing therein.

22. Liquid atomizing apparatus comprising a passage communicating with the liquid 70 to be atomized, an air jet in aspirating relation to the orifice of the passage and means for admixing a gaseous medium at less than the jet pressure with the liquid in the passage. 75

23. Liquid fuel combustion apparatus comprising an igniter and flame space, a fuel passage thereto, a source of liquid fuel supply at a lower level than the outlet from the passage and an entrance for a gaseous medium in said passage between said level 80 and the said outlet. 85

24. A liquid fuel combustion device adapted to maintain a continuous flame in a space of small compass, capable of operation by moderate pressure differences and adapted to be ignited electrically and comprising in combination, a flame space, an electric igniter therein, a supply of liquid fuel at a lower level and means for establishing an ignitable, steady-burning mixture in said space including a passage through which fuel is moved by suction from said supply to said space, an inlet to said passage admitting a gaseous medium thereto whereby 95 said medium is commingled with the fuel in transit to said space, means at the outlet of said passage for further subdividing the fuel and mixing it with said medium and means for coincidentally energizing said igniter. 100

25. A liquid fuel combustion device comprising, a flame space, an electric igniter therein and a body of liquid fuel at a lower level, in combination with means for establishing an ignitable and steady-burning mixture in said space comprising, a fuel-conducting passage through which fuel is moved from said body to said space, an inlet for air to said passage whereby air is commingled with the fuel in transit through said passage, means at the outlet of said passage for further mixing said fuel and said air, and an auxiliary entrance through which air is admitted to said space. 110

26. A liquid fuel combustion device comprising, a flame space, an electric igniter therein and a supply of liquid fuel at a lower level, in combination with a fuel-conducting passage between said space and supply, associated with a source of heat, and provided with an inlet admitting air thereto whereby air is commingled with the fuel and the commingled medium is heated in transit through said passage to the flame space, and means at the outlet of said passage for further mixing the fuel and air delivered to said space. 115

27. Combustion apparatus comprising a mixing and ignition space, electrically op- 120

erated means for creating flows of air and fuel into said space, means for mixing air with the fuel flow, electrically heated vaporizing means for the mixture, an electric igniter within said space and means for conjointly supplying current to all said electrical means.

28. Combustion apparatus comprising an ignition space containing an electric igniter, a passage through which air flows to said

space, means for delivering fuel into said passage, an electric heating element applied to said passage between the point of said delivery and said space and means for energizing said igniter when said element is 15 energized.

In testimony whereof, I have signed this specification.

JOHN GOOD.
